TABULATING MACHINE

James W. Bryce, Bloomfield, N. J., assignor, by
means assignments, to International Business
Machines Corporation, New York, N. Y., a cor-
poration of New York

Application October 30, 1930, Serial No. 492,183

9 Claims. (Cl. 235—92)

This invention relates to tabulating machines and more particularly to counter control mechanism therefor.

In tabulating machines of the type normally controlled by records having index point designations in columns it is customary to employ a plurality of entry receiving devices such as accumulators or printing elements and operate each entry receiving device in accordance with 5 designations in a particular index column of the record which normally is in the form of a perforated card. It is frequently desirable to make certain types of entries such as cash price and credit price, either of which may occur in the same field, into separate entry receiving devices, and to accumulate their combined sums in a 10 third entry device. In such cases it is desirable to conserve accumulating mechanism by utilizing a single accumulator for all of the above 15 types of entries of the same class entered in different fields of the record cards.

It may happen that different types of cards have similar information in differently located fields and it is desirable to accumulate the data 20 from such related fields into the same accumulator.

It is therefore an object of this invention to provide a system whereby entries from a plurality of differently located fields in successively 25 fed record cards may be selectively entered into a single data controlled device.

Another object is to provide a system whereby items in fields of a record card may be selectively entered into receiving devices in accordance 30 with the classification data of the record card.

A further object is to provide a system whereby data contained in differently allocated fields of successive record cards may be separately accumulated in accordance with the location of 35 the fields and collectively accumulated at the same time to obtain a sum of the separate accumulations.

Various other objects and advantages of my 40 invention will be obvious from the following 45 particular description of one form of mechanism embodying the invention or from an inspection of the accompanying drawings; and the invention also constitutes certain new and novel features of construction and combination of parts 50 hereinafter set forth and claimed.

In the drawings:

Fig. 1 is a detail of a fragment of one type of record.

Fig. 2 is a detail of a fragment of another 55 type of record.

Fig. 3 is a circuit diagram of a complete tabulating machine constructed in accordance with the invention.

Fig. 4 is a circuit diagram of a modification. In Fig. 1 is shown a type of card having fields 60 designated N and B representing "cost price" and "cash price" respectively. In Fig. 2 the corresponding fields A and M contain information relating to "cash price" and "credit price". If these cards were run through the normal tabulator, fields N and A would be added together and fields B and M would also be added together giving meaningless sums. To distinguish one type of card from the other a special 65 designating perforation is made in the card of Fig. 1 in the 11 or "X" index point position of a predetermined column as shown in column 70 16. The mechanism for sensing this hole will control the operation of the machine to cause fields A and B to be added together and also to be separately accumulated. A final result of 75 a run of promiscuous cards of the types of Figs. 1 and 2 will give separate totals of the data in fields A, M, N, and B and a combined 80 total of fields A and B. The mechanism involved in deriving this result will now be explained in detail.

Referring more particularly to Fig. 3 a tabulating motor TM controlled by associated contacts and relays 10 is employed for driving the tabulating machine during listing and tabulating operations and reset motor RM controlled by its associated relays and control circuits 11 is utilized for driving the machine during reset and totaling cycles. The above mentioned relays and control circuits are well known in the art and for further description thereof reference may be had to the copending application of C. D. Lake, Serial No. 639,153, filed May 15, 1923, now Patent No. 1,822,594, dated September 8, 1926. The machine is controlled in response to perforated record cards 12 by means 85 of a set of upper brushes 13 and a set of lower brushes 14. Group indicating contacts GI and group control contacts GC may be inserted in 90 the circuit between upper brushes 13 and lower brushes 14 if desired, the connections therefor being set forth in detail in the patent to Lake No. 1,600,413, dated September 21, 1926.

A plurality of banks of accumulating elements 105 A', B', C, M' and N' each comprising counter magnets 20 and printer magnets 21 connected in the usual manner are all adapted to be connected by plug connection to lower brushes 14. Banks A', and C are connected to brushes 14 110

which sense fields A—N of the record cards through relay coil 25 and its associated contacts 26 and 27 respectively. Bank M' is connected to brushes 14 which sense fields M—B of 5 the record cards through contacts 28. With the relay in the position shown, contacts 26, 27 and 28 are closed and entries may be received from fields A—N of the cards in banks A' and C simultaneously and from fields M—B in bank M'. 10 Energization of coil 25 will shift the multi-contact device to open contacts 26, 27 and 28 and close contacts 29, 30 and 31 thereby connecting brushes 14 of fields A—N to bank N' through contacts 29 and connecting brushes 14 of fields 15 M—B to banks B' and C through contacts 30 and 31 respectively.

Relay 25 is controlled by an index point designation in the record controlling the machine as will now be described. In the usual type of 20 Hollerith card ten index point positions are provided into which data for controlling the tabulating machine is entered. Two extra positions are also provided at the top of the card commonly called the 11 and 12 positions or the 25 "X" and "Y" positions. Since data are not ordinarily entered into these last two positions they may conveniently be selected for controlling the operation of relay 25. Assuming the "X" position to be selected, cam contacts 32 are designed to be closed only at the time the "X" index point position of the record card is under the upper brushes 13. If a perforation is then 30 encountered in this position by a brush 13 a circuit will be completed through relay coil 25 from left side of line 37 traced through contact 33, brush 13, hole in the "X" position, plug connection 34, contacts 32, coil 25 to binder post 35 at the right side of the line. Two cam contacts 32 are shown inasmuch as the time of 40 make and break may be more accurately determined than would be the case were a single cam member used and adjustment is thereby facilitated. Contact 33 is designed to open before the record card has passed brushes 13 in order 45 to avoid back circuits and also to avoid circuits being established between cards.

The coil 25 is controlled from brushes 13 to shift its associated contacts just before the card leaves these brushes. The actual entry of the 50 data designated on the card field into the selected banks occurs during the following machine cycle while the card is passing under brushes 14. The energizing circuit of coil 25 then, when once closed, must be maintained during that 55 portion of this following cycle in which the data designating portion of the card field is passing beneath brushes 14 and the circuit must be opened before the "X" index point position of the following card reaches brushes 13. A holding 60 circuit is therefore provided which runs from contacts 33, contacts 32 through relay coil 36 to post 35. Coil 36 closes its points 36a and a circuit is subsequently made from line 37, wire 38, cam contacts 39, points 36a, coil 25 to post 35.

The cam contacts 39 are designed to be automatically closed by the machine operation just prior to the closure of contacts 32 and to be 65 opened during the following machine cycle after the entire data designating portion of the card field has passed the lower brushes 14 but before the "X" index point position has reached such brushes. Just prior to the analyzing of the "X" index point position as explained above, the 70 holding circuit is broken by contacts 39 so that

the following record card may likewise energize the relay 25 or not depending on the presence or absence of a selecting perforation in its "X" index point position.

The apparatus just described operates as follows: If a record card contains no control perforation in its "X" point position of a predetermined column, the relay coil 25 remains unenergized, contacts 26, 27, and 28 remain closed and the data on the card of Fig. 2 in field A will be entered into the accumulator banks A' and C and that in field M will be entered into bank M' from the brushes 14 through the contact device and connections as shown. However, if a control perforation is present in the "X" position of the card as in Fig. 1, relay 25 is energized, contacts 26, 27 and 28 open and contacts 29, 30 and 31 close whereupon the data on the card in field B will be entered into banks B' and C and that in field N will be entered into bank N' through the plug connections as shown.

Thus where distinct types of cards contain related data in unaligned fields data may be collected into a common accumulator. Also a greater amount of data may be designated in a 100 lesser number of card columns, as for instance in the examples chosen, columns 1 to 8 are used to record "cash price" and "cost price" and columns 9 to 15 contain "credit price" and "cash price", the machine automatically separating the 105 unrelated items into appropriate counters for separate tabulation.

Thus at the end of a run of cards accumulator bank A' will contain a total of all "cash price" 110 items of the type of card in Fig. 2. Bank B' will contain a total of all "cash price" items of the type of card in Fig. 1. Bank C will contain a total of all "cash price" items of both types of cards, and banks M' and N' will contain separate totals of "credit price" items and "cost 115 price" items respectively.

It is sometimes desirable to enter two items simultaneously in a pair of totalizers and upon the occurrence of a specially designated card enter the two items in the pair of totalizers in 120 an inverse manner.

An arrangement whereby this can be accomplished is shown in Fig. 4. When a card such as shown in Fig. 1 but without the special hole in the sixteenth column controls the operation, 125 coil 25 is not energized. An item representing field N is entered by contacts 26 and wires 40 to totalizer N' M'. An item representing field B of the same card is entered by contacts 28 and wires 41 to totalizer A' B'.

When a special card such as that shown in Fig. 2 but provided with the special hole in the sixteenth column controls the machine coil 25 is energized, as previously described. Thereupon, the item of field A will be entered by contacts 29 and wires 42 to totalizer A' B', noting that the item of the same field of the card in Fig. 1 was entered in totalizer N' M'. The item represented by field M of the card shown in Fig. 2 will be entered by contacts 31 and wires 43 to totalizer N' M'.

It will be observed that to secure this result only two totalizers are necessary and the plug connections for the undesired ones are removed when employing this arrangement.

While there has been shown and described and pointed out the fundamental novel features of the invention as applied to a single modification, it will be understood that various omissions and substitutions and changes in the form and 180

details of the device illustrated and in its operation may be made by those skilled in the art without departing from the spirit of the invention. It is the intention therefore to be limited 5 only as indicated by the scope of the following claims:

What is claimed as new is as follows:

1. In a tabulating machine controlled by records having item representing index points arranged in columns, a plurality of totalizers, means whereby items in certain columns are entered in said totalizers, and means whereby a special index point causes the items in said certain columns to be entered into said totalizers 10 in transposed order.

2. In a tabulating machine controlled by records having item representing index points arranged in columns wherein several columns comprise a data field; there being a pair of 20 data representing fields, a pair of totalizers associated therewith and adapted to receive entries under control of the data representing fields and record controlled means adapted to cause the entries of both fields in the pair of 25 totalizers simultaneously, or to cause the entries to be effected simultaneously in the totalizers in a transposed order.

3. In an accounting machine adapted to be controlled by records in which data of the same 30 classification may be designated in different record fields of successive records, an accounting device, means for normally connecting said device for entry of data from a field of a record and means controlled by the classification designation on another record for automatically disabling the first named connecting means and connecting said accounting device to receive data under control of a different field.

4. In an accounting machine adapted to be 40 controlled by records in which data of the same classification may be designated in different record fields of different records, a plurality of sets of sensing devices adapted to analyze the several record fields, an accounting device, and means controlled by the absence or presence of 45 a classification designation on a record for automatically determining which of the sets of sensing devices related to the different controlling fields are to control the entries in the accounting device.

5. In a tabulating machine, a group of three 55 totalizers, means for connecting one of said totalizers to function as a grand totalizer to receive items entered under control of two different record fields of successive records, means controlled by the record characterization for connecting one or the other of the two remaining totalizers to receive items entered under control of the other field of the record in accordance with which record field controls an item entry in the grand totalizer, and analyzing

devices for controlling the different item entries.

6. In an accounting machine, a group of at least four totalizers, means for entering one or two items in a single machine operation, means for causing one of said totalizers to function as a grand totalizer to receive items entered during successive machine operations, means for causing two other totalizers of said group to separately totalize the last named items entered, and means for preventing another item entered during the same machine operation an item is entered in one of the two other totalizers mentioned from being entered in the grand totalizer and causing it to be entered in a related totalizer comprising the remaining totalizer of the group.

7. In a tabulating machine, a group of five totalizers, means under control of the records for entering an item represented by one of two different fields of successive records into a common totalizer of said group, means controlled by classification characteristics of records for causing the items represented by said fields to be selectively entered in two other totalizers of said group, and means for preventing the item 110 represented by the other record field of each controlling record from being entered in any of the totalizers mentioned and for causing said item to be entered selectively in another totalizer of the remaining two totalizers of the group. 115

8. In a tabulating machine controlled by records having designations comprising a plurality of card fields representing different classes of items, a plurality of totalizers and controlling elements therefor, analyzing brushes, one for 120 each card field, an electrical switch comprising a plurality of switch blades electrically connected to said brushes, contacts of said switch contacting with said blades to enter the items in said totalizers by electrical connections to 115 said controlling elements, and means for shifting said blades to cause contact with only other contacts of said switch and by other electrical connections to said controlling elements to enter items in said totalizers in a transposed manner. 120

9. In a tabulating machine controlled by records each having designated thereon at least two different controlling and item representing fields, a plurality of totalizers, means under control of a record having a single index point 125 designation at a common predetermined position of the records for effecting the entry of the items represented by the record having such designation in certain of said totalizers, and means dependent solely upon the absence of 130 the single index point designation at said common predetermined position of another record for causing the items represented thereon to be entered in certain other totalizers. 135

JAMES W. BRYCE.
